UNITED STATES PATENT OFFICE.

MARK S. HOTCHKISS, OF BINGHAMTON, NEW YORK.

SIDE-RAIL FORM FOR CONCRETE PAVEMENTS.

Application filed April 6, 1923. Serial No. 630,225.

To all whom it may concern:

Be it known that I, MARK S. HOTCHKISS, a citizen of the United States of America, of Binghamton, in the county of Broome, in 5 the State of New York, have invented new and useful Improvements in Side-Rail Forms for Concrete Pavements, of which the following, taken in connection with the accompanying drawings, is a full, clear, and exact 10 description.

This invention relates to a side rail form for concrete pavements of the class set forth in my pending application, Serial Number 464,631, filed April 26, 1921, except that the 15 rail is somewhat L-shaped in cross section and that its top portion overhangs the base plate and is provided with a downwardly projecting flange along its outer longitudinal edge adapted to be engaged by one or 20 more braces which rest upon the base plate to brace the entire rail and particularly, the free edge of the top and thus permits the passage of vehicles and other loads across the top portion of the rail with less liability 25 of springing or otherwise deforming the rail.

The main object is to provide a road rail of this character of relatively thin sheet metal not only for the purpose of economy 30 in manufacture, but mainly to facilitate the handling thereof in placing and removing the rails, it being understood that these rails are only temporarily used to define the outline of the pavement and are then removed 35 and replaced in other positions as the work progresses.

Another object is to provide means whereby the braces and rails may be secured in 40 place by the same stakes which are driven into the ground through registering apertures therein.

A further object is to provide simple and efficient means for alining the rail sections end to end both laterally and vertically.

45 Other objects and uses relating to specific parts of the device will be brought out in the following description.

In the drawings:

50 Figure 1 is a top plan of a portion of a pavement form showing opposite rail sections held in parallel spaced relation by cross braces constituting dividers for blocking off the pavement in similar lengthwise sections.

Figures 2, 3 and 4 are transverse sectional views taken respectively on lines 2—2, 3—3 and 4—4, Figure 1.

Figure 5 is a transverse vertical sectional view taken on line 5—5, Figure 1.

Figure 6, is a perspective view of one end 60 of one of the rail sections and one of the coupling braces in operative position thereon ready to receive the adjacent rail section.

Figure 7 is an inverted plan of portions 65 of the adjacent ends of the two rail sections showing the means for alining them vertically.

Figure 8 is a perspective view of the coupling brace shown in Figure 6.

Figure 9 is a longitudinal sectional view 70 partly broken away taken on line 9—9, Figure 7.

Figures 10 and 11 are perspective views 75 of different forms of braces used in supporting the outer edge of the top of the rail sections.

In Figure 1 is shown a pair of rail forms in parallel spaced relation according to the width of pavement required to form the lengthwise edges of said pavement as the intervening space is progressively filled in with concrete or other more or less plastic material preferably held in spaced relation by parallel transverse partitions or braces which also serve as dividers for marking 85 off the pavement into blocks of uniform length, said rails being preferably of comparative thin sheet metal of L-shaped cross section with their upright webs or sides facing each other with braces at suitable intervals lengthwise thereof, between the top and bottom portions for stiffening and alining purposes.

Each rail is preferably made in sections 95 —1— of convenient length for handling, arranged end to end and having the bottom portions of their adjacent ends provided with lengthwise extensions —2— those of one section projecting a relatively short distance along and against the underside of the next adjacent section to form a seat therefor, and thereby to hold the adjacent ends in horizontal alinement or in the same horizontal plane without in any way interfering with the free operation of the sections when desired.

The adjacent ends of the sections —1— are temporally coupled together by braces —3—

which also serve to align the meeting ends both vertically and laterally and to assist in supporting the top portions of the rail against downward deflection under load as will be hereinafter more fully explained.

Additional braces —4— and —4'— may be placed at suitable intervals along the rail sections between the top and bottom thereof for further supporting the top plates 10 against downward deflection under load.

The several rail sections —1— and braces are constructed and assembled in such manner as to enable them to be constructed of comparatively thin sheet metal which not only greatly reduces the cost of manufacture, but also facilitates the handling thereof thereby greatly expediting the work of placing, removing and transferring the forms.

20 The means for temporarily holding the rails in transversely spaced relation preferably consists of thin sheet metal plates —5— arranged in longitudinally spaced relation at suitable intervals along and between the 25 rails and interlocked therewith in a manner hereinafter described, so that they may be easily removed and replaced at will.

As illustrated, each rail section —1— is substantially L-shaped in cross section and 30 comprises a substantially flat upright web —6—, a base plate —7— and a top plate —8—, said base plate and top plate being integrally united to the lower and upper longitudinal edges of the web —6— and 35 projecting laterally to one and the same side thereof in parallel, vertically spaced relation so that the top plate —8— may overhang a portion of the base plate —7—.

The base plate —7— is of sufficient width 40 to enable it to support the rail section in an upright position when resting upon the ground or other suitable support and is of relatively greater width than that of the top plate —8—.

45 That is, the top plate is relatively narrow as compared with the width of the bottom plate and is provided along its outer edge with a relatively narrow downward turned flange —9— in spaced relation to the web 50 —6— to form a channel —10— in the under side of the top plate for receiving portions of the braces —3—, —4— and —4'—.

The web —6— may be of any suitable vertical height according to the thickness of 55 the concrete which is to be laid between the rails, but in all cases the top plate —8— and its flange —9— will be some distance above the base plate —7— to permit the free insertion and removal of the braces —3—, —4— and —4'— by lateral movement thereof toward and from the web —6—.

60 The base plate —7— is substantially flat and disposed in a plane at right angles to that of the web —6— so as to cause the latter to stand vertically when the base

rests upon the ground or other horizontal support, and is provided at suitable intervals just inside of its outer edge with holes —11— for receiving stakes as —a— which are driven therethrough into the ground to hold the rail section in a relatively fixed position against lateral movement when properly set, until limited by stops —a'— thereon.

65 The top plate —8— between the flange —9— and web —6— is also substantially flat and disposed in a plane at right angles with that of the web, and, therefore, parallel with that of the base plate —7—.

The down-turned flange —9— along the 70 outer edge of the top plate —8— is also substantially flat and disposed in a plane at right angles to that of the top plate —8—, and therefore, parallel with that of the web —6— and serves not only to stiffen the top 75 plate but also to form with the web, the intervening channel —10—.

80 The coupling brace —3— is also substantially L-shaped, but relatively short as compared with the length of the rail sections and comprises a substantially flat upright web —12—, a base plate —13—, and a top plate —14—, the base plate and top plate being formed integral with the lower and upper edges respectively of the web —12— 85 and are disposed in planes at substantially right angles thereto but extend laterally in opposite directions therefrom.

85 The web —12— is of substantially the same vertical height as the distance between the base plate —7— and top plate —8— of the rail section —1— and therefore, approximately equal to the inner face vertical width of the web —6—, while the transverse width of the top plate —14— is substantially equal to the distance between the flange —9— and web —6— and is provided along its outer edge with a down turned flange —15— for stiffening purposes and also to form a flat bearing face engaging the inner face of the web —6— when the parts are assembled.

90 The top plate —14— is, therefore, seated in the channel —10— against the underside of the top plate —8— while the base plate —13— rests upon the upper face of the base plate —7— of the rail —1— thus positioning the web —12— in parallel spaced relation to the web —6— and permitting the coupling brace —3— to slide freely lengthwise over and upon the adjacent ends of the rail sections —1— before the stakes are driven in place.

95 The base plate —13— of the coupling brace —3— is provided with vertical openings —16— adapted to be brought into registration with similar openings —11— in the adjacent ends of the base plate —7— of the rail sections for receiving stakes as —12— whereby the coupling brace —3— and 100

adjacent ends of the rail sections —1— will be held against endwise or lateral displacement with the rail sections in exact alignment both horizontally and vertically.

5 The assembling of these coupling braces upon the meeting ends of the rails is particularly simple and expeditious in that it is only necessary to bring the meeting ends of the rails into fairly approximate alignment after which the brace is slightly tilted with its top plate registered with the channel —10— and then the bottom plate is pushed inwardly thereby crowding the top plate —14— between the opposite side walls 10 of the channel —10— and at the same time bringing the base plate —13— into close contact with the upper face of the base plate 15 —7— of the rail sections —1— following which the coupling brace may be adjusted endwise to register its slots —16— with the slots —11— to permit the passage of the stakes —12— therethrough.

These stakes are usually tapered at their lower ends and serve to automatically draw the meeting ends of the rail sections together as the stakes are driven into the ground, it being understood that when the meeting ends of the rail sections are brought together, the extension —2— on the end of each rail section will be extended under the next adjacent section thereby assuring a close horizontal alinement of said rail sections in addition to that afforded by the coupling brace —3—.

35 The braces as —4— and —4'— for supporting the intermediate portions of the free edges of the top plates —8— of the rail sections —1— are also substantially L-shaped, the upright portions thereof being of substantially the same height as the distance between the base plate —7— and top plate —8— so that their bases as —17— and —17'— may rest upon the upper faces of the base plate —7— while their upper edges are provided with inner and outer flanges —18— and —19— as shown in Figure 10 or —18'— and —19'— as shown in Figure 11, the flanges of each brace being disposed in different vertical planes in spaced relation to form intervening grooves —20— and —20'— for receiving the flange —9—.

The base plates —17— and —17'— are provided with vertical openings —21— and —21'— adapted to register with similar openings —11— in the base plate —7— of the rail section —1— for receiving the stakes —12— which serve to hold the braces in operative position in addition to their main function of holding the rail against lateral or longitudinal displacement.

These braces —4— and —4'— are also slipped from the underside of the top plate —8— upwardly by registering the grooves —20— or —20'— with the flange —9— and the crowding of the base plate inwardly to-

ward the web —6— and the upper edges of the braces are positively interlocked with the said flange after which the stakes —12— are driven through the registering openings in the base plates of the braces and rail under which conditions the upright portions of the bases will be held in parallel spaced relation to the web —6— of the rail directly under the free edge of flange —9— of the top plate —8— so as to additionally stiffen the latter against downward deflection under load and, for example, in moving vehicles and other objects across the rails.

The extensions —2— on the ends of the rail sections —1— are preferably secured by spot welding or other suitable fastening means to the undersides of the base plate —7— so as to project a short distance beyond the ends thereof whereby the extension of each plate forms a seat for the end of the next adjacent plate and greatly assists in alining the plates in the same horizontal plane.

The partitions —5— are preferably made of sheet metal of any suitable length according to the width of the pavement which is to be laid and serve as spacing members arranged at intervals throughout the length of the rails, and also serve to divide the pavement of the blocks. 95

For this purpose, the opposite ends of the upper portion of each plate are provided with lateral hook-shaped extensions —22— adapted to enter slots —23— in the upper inner corners of the rail sections by downward sliding movement thereof, between the rails, the remaining portions of the ends of each partition being substantially straight and vertical so as to abut against the inner faces of the rails and thereby to assist in holding them in parallel spaced relation against inward displacement while the hook-shaped extensions engaging the outer faces of the webs —6— hold the plates against outward displacement, the vertical height of the partitions being substantially equal to that of the web —6—.

The construction of the rail forms is particularly simple, strong, and durable and enables the various parts thereof to be easily and quickly assembled and removed, thereby greatly facilitating the work of laying the forms and materially increasing the work accomplished for a definite period of time, but it is evident that certain changes may be made in the structural details without departing from the spirit of this invention.

I claim:

1. A side-rail form for concrete pavements comprising a substantially L-shaped rail section having a laterally projecting top portion overhanging its base portion in spaced relation thereto, and a substantially L-shaped brace section having its base and 130

top portions engaging respectively the base portion and overhanging top portion of a rail section, the bases of the rail and base sections being provided with registering openings for receiving stakes adapted to be driven therethrough into the ground.

2. A side-rail form for concrete pavements comprising a substantially L-shaped rail section having a laterally projecting top-portion overhanging its base portion in spaced relation thereto, and a substantially L-shaped brace section having its base and top portions engaging respectively the base portion and overhanging top portion of a rail section, the base of the rail section being provided with an end extension for receiving and supporting the end of another similar rail section at the same level.

3. A side rail form for concrete pavements, comprising L-shaped rail sections arranged end to end and provided with laterally projecting top portions overhanging their base portions in spaced relation thereto and L-shaped brace sections extending across the meeting ends of the rail sections between and against the bases and overhanging top portions of the rail sections, and stakes passed through registering openings in the bases of the rail and brace sections and adapted to be driven into the ground.

In witness whereof I have hereunto set my hand this 30th day of March, 1923.

MARK S. HOTCHKISS.
